UNITED STATES PATENT OFFICE

99,971

DESIGN FOR A HEDGE TRIMMER

Roy Yantis, Overland Park, Mission Township,
Kans.

Application March 23, 1936, Serial No. 61,732

Term of patent 14 years

To all whom it may concern:

Be it known that I, Roy Yantis, a citizen of the United States of America, residing in Mission Township, Overland Park, Johnson County, Kansas, have invented a new, original, and ornamental Design for a Hedge Trimmer, of which the following is a specification, reference being had to the accompanying drawing, forming a part thereof.

I claim:

The ornamental design for a hedge trimmer as shown.

ROY YANTIS.
